UNITED STATES PATENT OFFICE.

JOSEPH ROTCHILD, OF NEW YORK, AND HENRY S. CONOVER, OF BROOKLYN, NEW YORK, ASSIGNORS TO THE ROTCHILD PRESSURE SPECIALTIES COMPANY, OF CANTON, NEW YORK, A CORPORATION OF NEW YORK.

DISK VALVE.

1,014,775.

Specification of Letters Patent.

Patented Jan. 16, 1912.

Application filed May 16, 1910. Serial No. 561,569.

To all whom it may concern:

Be it known that we, JOSEPH ROTCHILD and HENRY S. CONOVER, citizens of the United States, residing at New York, in the county and State of New York, and Brooklyn, in the county of Kings and State of New York, respectively, have invented certain new and useful Improvements in Disk Valves, of which the following is a specification.

This invention relates to valves and its novelty consists in the construction and adaptation of the parts as will be more fully hereinafter pointed out.

15 In the drawings, Figure 1 is a longitudinal section of the valve casing and a side elevation of the parts contained therein; Fig. 2 is a longitudinal section on the plane of the line 2—2 in Fig. 1; Fig. 3 is a side

20 elevation of the valve disk and tiltable frame and a partial longitudinal section through the casing; Fig. 4 is a top plan view of the parts and a horizontal section through the casing on the plane of the line 4—4 in Fig.

25 1 and Fig. 5 is a perspective view of the valve spindle.

In the drawings, 10 is a tubular valve casing suitably threaded internally or externally at its ends so that it may be connected to the pipes which it is to control. It is preferably made of cast metal for instance cast iron and may be provided internally at one portion, where the valve hereinafter described is to be located, with 30 a lining or shell 11 of brass or other relatively soft metal. At a convenient point the casing is apertured and provided with an internally threaded external annular flange 12. At a diametrically opposite point

35 it is also apertured and provided with an internally smooth external annular flange 13 which may be inwardly extended to form an internal annular flange 130. It is also provided beneath the lower surface of the valve

40 with a series of threaded apertures 14, 14 adapted to receive supporting pins 15, 15 presently to be described.

A thimble 16 having a smooth cylindrical recess 17 and threaded externally is adapted 45 to be placed within the threaded aperture 12. The inner end of the thimble extends well within the casing. It is provided with a

stop flange 18 to limit its inward position and with a polyhedral extremity 19 so that it can be engaged like a hexagonal nut with 55 a wrench. This forms in effect a removable bearing for the valve frame trunnion.

A separable valve spindle 20 comprising a cylindrical body 21 is adapted to rotate within the annular flange 13 as a bearing. 60 Its inner end is expanded to form a stop flange 22 and it terminates in a squared head 23 adapted to engage an aperture in the cross-head presently to be described. A handle 24 is adapted to be secured to the 65 spindle 20 by a set screw 25 or by any other suitable means. A packing 26 of any suitable material may, if desired, be placed between the flange 22 and the inner wall of the casing 10 or flange 130 as the case 70 may be.

Suspended within the casing 10 is a tiltable valve frame comprising a cross head 30 having a depending flange 300 provided with an outwardly projecting trunnion 31 75 adapted to engage the cylindrical recess 17 of the thimble 16 and to turn within the same. It also has a depending flange 32 provided with a squared aperture 33 to receive the squared end 23 of the valve spindle 20. It also has an arm having a depending lug or flange 34 on one side and an arm having a similar depending lug or flange 35 on its opposite side. A valve member 40 consisting of a circular plate fitting 80 loosely within the casing 10 is provided with upwardly extending lugs arranged in pairs 41, 41, and 42, 42. A link 43 is pivoted by a pin 44 between the lugs 41, 41 at its lower end, and by a similar pin 440 to the flange 34 85 of the cross head 30 at its top and two links 45, 45 are pivoted by a cross pin 46 outside of the lugs 41, at their lower ends and by a similar pin 460 to the flange 35 at their 90 upper ends. These links are all of the same length and the centers of their pivots are all the same distance apart so that when the cross head 30 is tilted the valve plate 40 is necessarily simultaneously tilted to the same extent and in the same direction. 95

At the center of the plate 40 there is arranged a threaded boss 48 adapted to engage a threaded aperture in a lower valve plate 49 of substantially the same size and shape as

the plate 40. Between the plates 40 and 49 is arranged a packing ring 50 slightly greater in diameter than either plate and firmly held between them and adapted 5 when the plates are tilted by means of the movement of the cross head 30 tightly to engage the inner walls of the valve casing or of its lining 11.

The pins 15 have a threaded body 150, and 10 a squared head 151 and an inner smooth end 152. They may be of any size or number and arranged in any desired manner around the casing.

It is obvious from the foregoing description that when the handle 24 is tilted, the 15 cross head 30 will be tilted, because the square head 23 of the spindle 20 will engage the squared aperture in the flange 32 and the trunnion 31 will turn freely in the thimble 16. The tilting of the cross head will also tilt the links 43 and 45, drawing the link or links up on one side and down on the opposite side and thus moving the valve 20 plates 40 and 49 and packing ring 50 either 25 to the position shown in full outline in Fig. 2 from the position shown in dotted outline in Fig. 3, or vice versa.

The limit of tiltness of the framework composed of the cross head and its links is 30 determined by a stop member 430 secured to one of the links and which will engage the surface of the cross head when a predetermined amount of movement has taken place.

The pins 15 are designed to form an additional support for the lower valve plate 49 when the pressure upon the upper valve 35 plate is excessive. It enables the valve to be used in conduits when the fluid pressure is very great.

40 The valve is a truly balanced valve because the pressure is the same on each side of the medial plane passing through the center of oscillation of the cross head.

The parts of this valve are simple in construction and can readily be made by ordinary machine tools without any special mechanism. They are readily assembled and kept in order and readily removed from the casing when it is desired. The valve is 45 efficient even under unusual pressures and is readily moved by means of the handle provided for that purpose.

What we claim as new is:—

1. The combination with a valve disk of a 50 tilting frame work consisting of a cross head, two transverse pivots secured thereto, brackets secured to the valve disk, two transverse pivots secured thereto and links secured to the pivots on the cross head and 55 the corresponding pivots on the valve disk.

2. A tilting frame for a valve disk comprising a cross head provided on one side with a laterally extending pivot and on the other side with means for turning it consisting 60 of a squared aperture and a key pro-

vided with a handle adapted to fit therein, in combination with a valve disk and connections between it and the cross head.

3. A tilting frame for a valve disk comprising a cross head, means for oscillating 70 it, two depending links pivoted one on one side of the center of oscillation and one on the other side, in combination with a valve disk and pivot connections between it and the links.

4. A tilting frame for a valve disk comprising a cross head, means for oscillating it consisting of a pivot on one side and a handle on the other, two depending links pivoted one on one side of the center of oscillation 80 and one on the other side, in combination with a valve disk and pivot connections between it and the links.

5. A tilting frame for a valve disk comprising a cross head provided with two arms 85 extending therefrom in opposite directions, pivoted links depending from the arms and a valve disk to which the links are secured at their other ends.

6. A tilting frame for a valve disk comprising a cross head provided with two arms 90 extending therefrom in opposite directions, pivoted links depending from the arms and a valve disk to which the links are secured at their other ends, in combination with means 95 for oscillating the cross head.

7. A tilting frame for a valve disk comprising a cross head provided with two arms 100 extending therefrom in opposite directions, pivoted links depending from the arms and a valve disk to which the links are secured at their other ends, in combination with means for oscillating the cross head consisting of a removable detachable handle.

8. A tilting frame for a valve disk comprising a cross head provided with two arms 105 extending therefrom in opposite directions, pivoted links depending from the arms and a valve disk to which the links are secured at their other ends, in combination with means 110 for oscillating the cross head consisting of a pivot on one end and a detachable handle on the other end.

9. A tilting frame for a valve disk comprising a cross head provided with two arms 115 extending therefrom in opposite directions, pivoted links depending from the arms and a valve disk to which the links are secured at their other ends, in combination with means for oscillating the cross head consisting of a pivot on one end and a detachable handle on the other end in combination with 120 a valve casing inside of which the frame is placed and in which it is adapted to oscillate.

10. A tilting frame for a valve disk comprising a cross head provided with two arms 125 extending therefrom in opposite directions, pivoted links depending from the arms and a valve disk to which the links are secured at their other ends, in combination with 130

- means for oscillating the cross head consisting of a pivot on one end and a detachable handle on the other end in combination with a valve casing provided with a removable bearing to receive the cross head pivot and means for permitting the engagement of the handle.
11. A tilting frame for a valve disk comprising a cross head provided with two arms extending therefrom in opposite directions, pivoted links depending from the arms and a valve disk to which the links are secured at their other ends, in combination with means for oscillating the cross head consisting of a pivot on one end and a detachable handle on the other end in combination with a valve casing provided with a removable bearing to receive the cross head pivot and a fixed bearing to receive and support the handle.
12. A tilting frame for a valve disk comprising a cross head provided on one side with a laterally extending pivot and on the other side with means for turning it consisting of a squared aperture and a key provided with a handle adapted to fit therein, in combination with a valve disk and connections between it and the cross head and means for limiting the extent to which it may be turned.
13. A tilting frame for a valve disk comprising a cross head, means for oscillating it, two depending links pivoted one on one side of the center of oscillation and one on the other side, in combination with a valve disk and pivot connections between it and the links and means for limiting the extent of its oscillation.
14. A tilting frame for a valve disk comprising a cross head, means for oscillating it, two depending links pivoted one on one side of the center of oscillation and one on the other side, in combination with a valve disk and pivot connections between it and the links and means for limiting the extent of its oscillation consisting of a stop secured to one of the links.
15. A tilting frame for a valve disk comprising a cross head, means for oscillating it consisting of a pivot on one side and a handle on the other, two depending links pivoted one on one side of the center of oscillation and one on the other side, in combination with a valve disk and pivot

connections between it and the links and means for limiting the extent of its oscillation.

16. A tilting frame for a valve disk comprising a cross head, means for oscillating it consisting of a pivot on one side and a handle on the other, depending links pivoted one on one side of the center of oscillation and one on the other side, in combination with a valve disk and pivot connections between it and the links and means for limiting the extent of its oscillation consisting of a stop secured to one of the links.

17. A tilting frame for a valve disk comprising a cross head provided with two arms extending therefrom in opposite directions, pivoted links depending from the arms and a valve disk to which the links are secured at their other ends and means for limiting the extent of its oscillation.

18. A tilting frame for a valve disk comprising a cross head provided with two arms extending therefrom in opposite directions, pivoted links depending from the arms and a valve disk to which the links are secured at their other ends and means for limiting the extent of its oscillation consisting of a stop secured to one of the links.

19. A tilting frame for a valve disk comprising a cross head provided with two arms extending therefrom in opposite directions, pivoted links depending from the arms and a valve disk to which the links are secured at their other ends, in combination with means for oscillating the cross head and means for limiting the extent of its oscillation.

20. A tilting frame for a valve disk comprising a cross head provided with two arms extending therefrom in opposite directions, pivoted links depending from the arms and a valve disk to which the links are secured at their other ends, in combination with means for oscillating the cross head and means for limiting the extent of its oscillation consisting of a stop secured to one of the links.

In testimony whereof we affix our signatures in presence of two witnesses.
